UNITED STATES PATENT OFFICE.

ROBERT WOOTTON, OF BIRMINGHAM, ENGLAND, ASSIGNOR TO THE BRITISH TUBE COMPANY, LIMITED, OF SMETHWICK, ENGLAND.

MACHINERY FOR MANUFACTURING SEAMLESS STEEL TUBES.

SPECIFICATION forming part of Letters Patent No. 577,907, dated March 2, 1897.

Application filed January 20, 1896. Serial No. 576,188. (No model.) Patented in England March 15, 1895, No. 5,478.

To all whom it may concern:

Be it known that I, ROBERT WOOTTON, gentleman, a subject of the Queen of Great Britain, residing at 113 Harborne Road, Edgbaston, Birmingham, in the county of Warwick, England, have invented certain new and useful Improvements in Machinery for the Manufacture of Seamless Steel Tubes, of which the following is a specification.

10 This invention has been patented in England, No. 5,478, dated March 15, 1895.

My invention has for its object improvements in machinery for the manufacture of seamless steel tubes, and refers to the releasing of the tubes from the mandrels upon which they have been drawn; and it consists of various arrangements, as hereinafter described, for allowing the tube to be more readily inserted and removed from the machine and for 20 so operating upon the tube that it can be quickly removed from the mandrel, and at the same time is not materially marked during its passage through the machine.

In order that my invention may be clearly understood and more easily carried into practice, I have appended hereunto a sheet of drawings upon which I have fully illustrated the nature of my said improvements, together with the mode of and means for carrying the 30 same into effect.

Figure 1 is a cross-section through one of my machines. Fig. 2 is an elevation of the one side of same. Fig. 3 is a plan. Fig. 4 is an elevation of the other side. Fig. 5 is an elevation of the front or feeding end of the machine. Fig. 6 is a part section similar to Fig. 1, but showing a modification. Fig. 7 is an enlarged view of the bar C. Fig. 8 is also an enlarged view showing a modification. Fig. 9 is a similar view to Fig. 7, showing a further modification.

In carrying my invention into effect I mount in a suitable frame two rolls B and B', the axis b⁴ and b⁵ of which are parallel in one 45 plane, *i. e.*, in this instance, as viewed in plan, Fig. 3, and at an inclination to each other in the reverse plane, as viewed in the side elevation, Fig. 2, the bar C being arranged intermediately between the two. The roll B is 50 provided with only one operating-point, while that of B' has three—viz., B', B², and B³. The

tube Z is fed into the triangular space formed between the said rolls and the bar, which creates a screwing action upon the tube and thus raises up the metal from the mandrel, at the 55 same time tending to turn the tube on the mandrel and thereby release it. The rollers may be driven through any suitable mechanism, as toothed or worm gearing.

It is important that the tube Z should be 60 capable of being quickly inserted in the machine and again removed after the tube has passed the bite of the rolls without waiting for the whole of the remaining part of the mandrel to pass through, to effect which I 65 mount the roll B in the bearing-blocks a², which are made to slide in the main frame A and are operated by the springs J, so as to keep the roll B normally up to its work; but for the insertion of the tag of the tube and 70 the removal of the uncovered part of the mandrel the blocks a² are drawn back, so as to compress the springs J, this being effected by means of the wedge h², which forces out the strap or box H, the latter being connected by 75 the rods h' with the before-mentioned bearing-blocks a². The wedge is operated by the lever h³, which is pivoted at h⁴ and has a foot-stirrup attached at h⁵, by which the pressure of the roll B can be removed by the foot. 80 The roll B' is mounted in similar sliding bearing-blocks a' to that of B, and for the purpose of adjusting the position of the roll for the accommodation of various-sized tubes the pins e' are provided, which are provided with 85 the screw-thread, the frame A being tapped to receive them, and are provided with the worm-gear E and e² with connection-shaft e³ and square head e⁴ for attachment of handle, by which the roll B can be brought nearer to 90 or farther from the center, as may be desired. To obtain the full pressure of the rolls B and B' immediately the tag is inserted between them and before it reaches the point B³ of the roll, I may provide the rollers F and F', the 95 position of the one F of which may be adjusted by the screw-pin f², while that of F' is actuated by the spring f⁴ through the projection f³, the roller being drawn back by the handle f⁵ for the insertion of the tube. 100

For forming a durable and wearing surface without marking the tube the bar C is formed

trough shape, as shown, and is filled in with any suitable wood C', the grains of which are arranged to run vertically, or in place of this I may cover the bar with leather or other suitable material c⁴, or instead of wood I may use papier-mâché or other suitable composition, or I may provide one or a series of balls c², which would be mounted in the bar with a cover-plate c³, or they may simply fall into a long groove one against another.

Instead of moving the block a², as herein-before described, I may move the bar for the insertion of the tag, in which case the bar C would be mounted on a series of inclined planes M, which would be drawn up during operation upon the tube by the action of the wedge m³ upon the strap m', the inclined planes being carried back when the wedge is not in action by the spring m². The wedge may then be actuated by a lever m⁴ in a similar manner to that before described. I may vary the gearing and general details of the machine without departing from my invention.

25 What I claim, then, is—

1. In combination in a tube-forming ma-

chine, the pair of spindles b⁴, b⁵ arranged in parallel vertical planes and at an angle to each other in the horizontal plane, a series of rollers on one shaft of substantially the same 30 diameter relative to each other and a single roller on the other shaft arranged to coact with one of the series of rollers, and a bar C acting in conjunction with the single roller and with the series of rollers, substantially 35 as described.

2. In combination with the pair of spindles and the rollers thereon for acting upon the tube, the supporting-bar C having a yielding wearing-surface, substantially as described. 40

3. In combination with the pair of spindles and the rollers thereon for acting upon the tube, the supporting-bar C having a yielding wearing-surface formed of wood or like material, substantially as described. 45

In testimony that I claim the foregoing as my own I affix my name in the presence of two witnesses.

ROBT. WOOTTON.
